UNITED STATES PATENT OFFICE.

TOICHI FURUTO, OF PENNANT, SASKATCHEWAN, CANADA.

BINDER-ROLLER HOLDER.

Application filed December 18, 1923. Serial No. 681,452

To all whom it may concern:

Be it known that I, TOICHI FURUTO, a citizen of the Dominion of Canada, and resident of Pennant, in the Province of Saskatchewan and Dominion of Canada, have invented certain new and useful Improvements in Binder-Roller Holders, of which the following is a specification.

This invention relates to improvements in binder roller holders and the object of the invention is to provide means for securely holding binder rollers when replacing the repair pieces thereon.

Further objects are to provide means of this kind for holding the roller firmly itself, that will hold any kind of wooden roller.

With the foregoing and other objects in view, the invention consists essentially of the device, an embodiment of which is described in the present specification and illustrated by the accompanying drawings that form part of the same.

Referring to the drawings, in which like characters of reference indicate corresponding parts in each figure.

Figure 1 is an end view of a roller fitted with an embodiment of my device.

Figure 2 is a side elevation.

Figure 3 is a side elevation of the device, apart from the roller.

In the drawings, in which an embodiment of my device is illustrated, A represents a binder roller and B a chain adapted to encircle it. One end of this chain B is provided with a ring 10 while mounted on the other end is a sliding ring 11.

12 is a hook member substantially semi-circular in formation and provided at one end with a bent point 13 adapted to engage the wooden surface of the roller A, while 14 are a plurality of notches in the pin

adapted to engage with the ring 11 on the end of the chain B.

15 is a pin adapted in operation to prevent the ring 11 from becoming disengaged from the hook member.

In operation, the hook member 12 is set on the roller A and the sliding ring 11 on the right top of the roller. Then the chain B is brought around the roller once and a suitable rod or pin, as shown in dotted lines, passed through the end ring, the roller being turned slowly with hand until one end of the pin or rod catches against the roller, the other end being held by hand.

As many changes could be made in the above construction and many apparently widely different embodiments of my invention within the scope of the claims, constructed without departing from the spirit or scope thereof, it is intended that all matter contained in the accompanying specification and drawings shall be interpreted as illustrative and not in a limiting sense.

What I claim as my invention is:

1. A holder for binder rollers comprising a hook member adapted to engage a binder roller and formed with a plurality of notches therein, a chain adapted to embrace the roller and provided with links at each end.

2. In a device of the character described, the combination with a binder roller, of a hook member designed to engage said roller, a plurality of notches in said hook member and a chain adapted to embrace the roller and having links at each end designed to engage with the notches in said hook member.

In witness whereof I have hereunto set my hand.

TOICHI FURUTO.
